CATCHER

Albanus G. Delany, Alabama City, Ala., assignor
to Gulf States Steel Company, a corporation
of Delaware

Application April 22, 1933, Serial No. 667,343

6 Claims. (Cl. 80—43)

My invention relates to mechanical means for catching sheets and like rolled product from the forming rolls of a mill and automatically returning the sheets or stock for further passes through the forming rolls until it has been rolled to the desired gauge, when the catcher means will automatically discharge it.

The object of my invention is to devise an apparatus of the character described which shall be simple and sturdy of construction, rapid and effective in operation, and comparatively inexpensive as to cost of installation and operation.

My invention contemplates utilizing coacting pairs of reversely driven pincher rolls which act simultaneously on the rolled stock, the pair adjacent to the mill serving as "forwarding" rolls to move the rolled stock away from the mill against the action of the other or "reversing" pair of rolls which take charge of the stock as soon as it clears the forwarding rolls and act to check its momentum quickly, to reverse it almost instantaneously, and to permit it automatically to shift or assume such a position that on reversal it will take the proper path for its return to the mill.

My invention further contemplates associating with the reversing pincher rolls a chain, belt or conveyor, normally driven in the same direction as the reversing pincher rolls, which receives the stock as it is fed through said rolls and assists the latter in promptly checking and reversing the stock until the rolling cycle is completed when the conveyor is reversed and acts to discharge the finished stock.

My invention further contemplates adapting the drive for the reversing pincher rolls, and also the conveyors when they are used, to be reversed when the rolling cycle operation is completed, this reversal being automatically accomplished responsive to the control of the mill screw down means which acts to adjust the pass clearance between the forming rolls. When the screw down sets the rolls for the last pass it will, at the same time, trip a control which acts to reverse the drive of the reversing pincher rolls and the conveyor so that they will coact with, rather than to act in opposition to, the forwarding pincher rolls in effecting a rapid discharge of the finished stock. When the screw down means resets the rolls for the initial pass of a new rolling cycle it again acts automatically to reverse the drive for the reversing pincher rolls and conveyor.

My invention also contemplates, in its preferred embodiment, associating a third pincher roll with the upper forwarding pincher roll so as to form

therewith a pair of supplemental pincher rolls which will coact with the reversing rolls in effecting the return of the sheet or partly rolled stock to the mill. This is important where short stock is being rolled.

My invention also contemplates that all of the rotating elements in the catcher shall be constantly driven throughout a rolling cycle without there being any interruption or reversal except at the completion of the rolling cycle when the reversing pinch rollers and conveyor are reversed to discharge the finished stock.

My invention further contemplates so relating the reversing pincher rolls and the conveyor or stock support associated therewith, that the rear end of the partly rolled stock, as soon as it clears the forwarding rolls, will automatically and instantaneously rock or spring into position to direct the stock into the path provided for its return travel to the mill. This is preferably accomplished by permitting the stock to rock between the reversing rolls as a fulcrum as soon as its rear end clears the forwarding rolls, which rocking action will not only present its rear end in a position to enter the pass between the supplemental pincher rolls that coact to return to the mill, but will also bring its body into full engagement with the conveyor so as to make more effective its frictional engagement therewith.

Apparatus embodying features of my invention is illustrated in the accompanying drawings, forming a part of this application, in which:

Fig. 1 is a longitudinal sectional view through the forming rolls of a sheet mill and my improved catcher mechanism associated therewith;

Fig. 2 is a detailed view illustrating the manner of mounting of the three pincher rolls adjacent to the mill;

Fig. 3 is a detail plan view of the driven reversing pincher roll and the driving chains therefor which serve as a conveyor means for the stock.

Fig. 4 is a view similar to Fig. 1 showing a modification of my catcher mechanism in which the conveyor and supplemental reversing roll are omitted and both rolls of the pair of reversing rolls are driven; and

Fig. 5 is a detail view showing the drive for the reversing pincher rolls of Fig. 4.

Referring to the drawings for a better understanding of my invention, I show a pair of forming rolls 10 and 11 mounted in a suitable frame work 12. At 13 I show a screw down shaft operated through a gear 14 and meshing arm 16 from a reciprocable arm 17, the purpose of which is to regulate the relative positions of the form-

ing rolls to provide proper clearances for the several passes of each rolling cycle. Inasmuch as these features are well understood in the art, details of the construction and mounting have been omitted.

After passing between the rolls 19 and 11 the sheets or other rolled stock are received by a pair of lower rear guides 6 which direct same upwardly to the catcher and into engagement 10 with its pincher rolls. The catcher comprises preferably a trio of rolls 19, 20 and 21 disposed adjacent to and slightly above the pass in the forming rolls. The lower roll 19 and the upper roll 21 are mounted rigidly in a frame 22, while 15 the middle roll 20 of the trio is mounted in bearings 23 which bearings are held to the frame 22 by means of bolts 24 having springs 25 interposed between the bearings and the frame whereby the roll 20 is pressed into frictional engagement with the rolls 19 and 21.

The lower roll 19 of the trio is continually driven in the direction indicated by the arrow by a motor 26, and the other two rolls of the trio are frictionally driven in the manner just explained from the lower roll 19.

Disposed to the rear of the trio of pincher rolls just described is a pair of drive chains 27 serving as a conveyor for the rolled stock and driven by a reversible motor 28 controlled by a reversing switch 29 mounted on the reciprocable arm 17 of the screw down means. A pair of lugs 31 and 32 are mounted on the frame 22 in a position to be engaged by the arm 33 of the reversing switch 29 as the screw down means is operated. When the screw down means is slackened off, the arm 33 is engaged by the lug 32 to cause the motor 28 to drive the chains 27 in a direction opposite to the direction of movement of stock being received from the forming rolls 10 and 11 and the forwarding pincher rolls 19 and 20. When the screw down means has been tightened down sufficiently for the arm 33 to be engaged by the lug 31, the motor 28 will be reversed and the catcher chains 27 are driven in a direction corresponding to that of the sheets received from the forming rolls 10 and 11 and will discharge the finished stock. The quick reversal of the sheets, however, is brought about by means of a pair of reversing pinch rolls comprising a lower roll 35 driven by the chains 27 and an idler roll 36 mounted in a yoke 37 on the frame 22. The sheets are forced by the pair of forwarding pincher rolls 19 and 20 through the pass between the reversing pincher rolls 35 and 36 which are rotating in a direction to oppose this movement of the stock.

The pincher rolls 19, 20 and 21 are driven continuously in one direction without reversal during the rolling operation. The pincher roll 35 will be continuously driven in a counter-clockwise direction during each rolling cycle until at the conclusion thereof it is reversed to discharge the finished stock. In like manner, the upper flight 65 of the conveyor chains moving over suitable tracks 38 will normally be traveling counter to the approach of the unfinished stock along the path indicated by the dotted arrow 39 in Fig. 1. Both the roll 35 and the chains 27 will thus be 70 opposing by friction the forward movement of the unfinished stock which will be pressed against the reversing roll 35 by the weight of the idler roll 36. The roll 35 is set slightly above the level of roll 19 so that the stock tends to arch before engaging the chains 27. The moment the rear end of

the stock clears the forwarding pincher rolls 19 and 20 it is free to snap upwardly into engagement with the roll 21 and at the same time the stock beyond the rolls 35 and 36 will drop down into full engagement with the chains 27. When 5 this occurs the reversing pincher rolls and the chains 27 act to check and quickly reverse the stock and force it into the pass between the pincher rolls 20 and 21, then serving as supplemental reversing rolls and acting to return the 10 stock through guides 40 back to the mill, where it enters a pass between the forming roll 10 and an idler roll 41, which is typical of any idle or forming pass for the mill.

The catcher repeats the above operation for 15 a predetermined number of forming passes, but when the rolls 10 and 11 are set by the screw down means for the last forming pass, the motor 28 will be reversed in the manner described and there will be nothing to oppose the forward movement of the rolled stock as both the rolls 35 and 36 and the chains 27 will then be so driven as to effect the final discharge from the catcher of the finished stock.

In Fig. 4 I show a modified arrangement of 25 pincher rolls, the pair of forwarding rolls 19 and 20 being spring-pressed together as already described and acting to force the stock between the pair of reversing pincher rolls 35 and 36 and onto a downwardly inclined support 42. The 30 motor 28 is direct connected by drive chains 43 to the sprockets 44 fast on the journals of roll 35. The sprocket gear 45 fast on a journal of roll 35 meshes a gear 46 fast on a journal of the roll 36 so as to drive this roll also. A stop 47 is disposed to engage the yoke 37 so as to prevent it swinging far enough to interrupt proper mesh of the long teeth of the gears 45 and 46. These gears will, however, permit the rolls to open amply for the easy reception of the stock being 40 rolled.

I have dispensed with the upper pincher roll 21 and rely on the drive from both rolls 35 and 36 to reverse and force the stock back up the guides 40 into engagement between the rolls 10 and 41. 45 The increased frictional engagement of the two driven reversing rolls on the stock will be sufficient to check and quickly reverse it without the use of the conveyor chains 27 of Fig. 1, and when the rolls 35 and 36 are reversed, they will dispose 50 of the finished stock onto the inclined support 42 down which it will slide to be stacked or otherwise handled.

It will be appreciated that although I have 55 illustrated my invention in connection with a two roll mill, it is clearly adapted for operation with other types of mills, and it is to be distinctly understood that I am not limited to the specific construction shown. It is contemplated that my improved catcher means is adaptable for use with 60 any type of mill where it is desired to reverse the direction of movement and repass the sheets through the forming rolls.

In observing my improved catcher in operation, I found it impossible to detect with the eye a 65 distinct stopping of the movement of the sheets, the reversal of their movement being accomplished so quickly.

This quick return of the sheets is of special 70 importance in hot rolling practice where the extent of permissible reduction of the stock, without reheating, is dependent on the rapidity with which the catcher means will pass it back and forth or with shuttle action through the mill passes. It is also of great importance in its 75

bearing on the rolling capacity of the mill. By avoiding any shifting of catcher parts and any reverse of its driven parts during the rolling cycle I can cause the catcher to function with the maximum celerity and a minimum wear on parts, it being obvious that there will be no difficulty about the reversal of the chains 27 and small roll 35 to discharge the finished stock.

When I referred to the rolls of a pair of pincher rolls as driven, I mean to include either or both being driven and while I have not shown the roll 36 as driven, this may be done in any convenient way if desired. It will always be essential that the action of the forwarding rolls shall prevail over the reversing rolls but the latter should act to stop and reverse the stock before its rear end passes from between the reversing rolls when no conveyor chains 27 are employed. When such chains are employed they will assist the reversing rolls to stop and reverse the stock and will also return the stock to the reversing rolls if it happens to run past same, but the latter operation is not contemplated as it will slow up the operation.

While I have shown my invention in but two forms, it will be obvious to those skilled in the art that it is not so limited, but is susceptible of various changes and modifications, without departing from the spirit thereof, and I desire therefore, that only such limitations shall be placed thereupon as are imposed by the prior art or as are specifically set forth in the appended claims.

What I claim is:—

1. A rolling mill catcher, comprising a pair of forwarding pincher rolls driven to force stock away from the mill, a pair of pincher rolls beyond said forwarding rolls and having a reversible drive to force stock towards or away from the mill, said latter rolls being less powerful than said forwarding rolls and being disposed and normally driven to act on the stock simultaneously with and in opposition to said forwarding rolls, means to guide the stock back to the mill, and means to position stock requiring further reduction, when released to the exclusive control of said reversible rolls, to clear the forwarding rolls and coact with said guide means.

2. A rolling mill catcher comprising two pairs of pincher rolls disposed and reversely driven so as to act simultaneously and in opposition to each other on stock requiring further reduction, the pincher rolls nearer the mill being the forwarding rolls and more powerful than and disposed with their pass lower than the pass of the returning rolls, and the pairs of pincher rolls being relatively disposed to cause the stock when released by the forwarding rolls into the exclu-

sive control of said returning rolls to assume automatically position to clear said forwarding rolls and be returned to the mill.

3. In a catcher for a rolling mill, a pair of continuously driven forwarding pincher rolls, a pair of less powerful reversing pincher rolls normally driven contemporaneously with and in opposition to said forwarding rolls and between which the rolled stock is forced by the forwarding rolls, a table for supporting the stock beyond the reversing rolls, said reversing rolls and table being disposed with relation to the forwarding rolls so that the stock as it is released by the forwarding pincher rolls will automatically assume a position to pass the forwarding rolls on its return to the mill by the reversing pincher rolls, and means to reverse the drive of said reversing rolls to discharge the finished stock.

4. The combination with a catcher means for returning rolled product to a rolling mill, of a trio of guide rolls interposed between the mill and the catcher means and comprising a lower driven roll, a spring-pressed pincher roll coacting therewith to forward rolled stock from the mill to the catcher means, and an upper roll with which said spring-pressed pincher roll coacts to form an upper pair of rolls for returning the rolled product from the catcher means to the mill, the catcher means being disposed so that the stock will automatically shift from said lower to the upper pass upon being reversed by the catcher.

5. In a catcher means for rolling mills, in combination with a screw down adjustment for the mill rolls comprising an actuator, of a sheet catcher comprising moving sheet-engaging elements having a reversible drive, means to force a sheet into said catcher counter to the frictional effect of its moving parts, means to return a sheet from said catcher to the mill, and means tripped by said actuator to reverse the normal catcher drive only when a sheet is ready for discharge.

6. In a catcher means for rolling mills, the combination with a screw down adjustment for the mill rolls comprising an actuator, of a sheet catcher comprising moving sheet-engaging elements having a reversible drive, means to force a sheet into said catcher counter to the frictional effect of its moving parts as normally driven, means to return a sheet from said catcher to the mill, and means tripped by said actuator to reverse the normal catcher drive only when a sheet is ready for discharge and to restore the normal drive of the catcher after the discharge of the sheets.

ALBANUS G. DELANY.
